UNITED STATES PATENT OFFICE.

GEORGE KALKBRENNER, OF NEW YORK, N. Y.

DESIGN FOR A LINK CUFF-HOLDER.

SPECIFICATION forming part of Design No. 33,160, dated September 4, 1900.

Application filed August 9, 1900. Serial No. 26,445. Term of patent 14 years.

To all whom it may concern:

Be it known that I, GEORGE KALKBRENNER, a citizen of the United States, and a resident of the city of New York, borough of Manhattan, in the county and State of New York, have invented and produced a new and original Design for a Link Cuff-Holder, of which the following is a specification, reference being had to the accompanying drawings, forming a part

o thereof, in which—

Figure 1 is a plan view of a link cuff-holder embodying the features of my design, and Fig. 2 is an edge view or side elevation of the holder.

5 The design consists of a fluted twin shank A, continued at one end in the form of an elongated loop B, the outer extremity of which loop is given such an inclination that this portion of the loop is at an angle to the body o thereof. At the opposite end of the twin shank A a hook D is formed, which simulates the

hook of a shepherd's crook. In the formation of the bow or loop section of the hook humps C are formed in the opposing surfaces of the shank, and the free end E of the hook 25 is curved from the shank, while that portion of the hook between the bow or loop section and said free end is curved in direction of the shank.

Having thus described my invention, I 30 claim as new and desire to secure by Letters Patent—

The design for a link cuff-holder herein shown and described.

In testimony whereof I have signed my 35 name to this specification in the presence of two subscribing witnesses.

GEORGE KALKBRENNER.
